US0D1066553S

(12) **United States Design Patent** (10) **Patent No.:** **US D1,066,553 S**
(45) **Date of Patent:** **** Mar. 11, 2025**

(54) **WEAPON SIGHT**

(71) Applicant: **Crimson Trace Corporation**,
Columbia, MO (US)

(72) Inventors: **William A. Planck**, Columbia, MO
(US); **Tim Meissen**, Columbia, MO
(US); **Michael Cottrell**, Ashland, MO
(US); **Shane Ball**, Columbia, MO (US)

(73) Assignee: **Crimson Trace Corporation**,
Columbia, MO (US)

(**) Term: **15 Years**

(21) Appl. No.: **29/822,330**

(22) Filed: **Jan. 7, 2022**

(51) LOC (15) Cl. **22-01**

(52) U.S. Cl.

USPC **D22/109**

(58) **Field of Classification Search**

USPC D16/130, 132, 133, 220; D21/572-574;
D22/108, 109, 110, 199; D26/38, 60

CPC F41G 1/00; F41G 1/32; F41G 1/35

See application file for complete search history.

CLAIM

The ornamental design for a weapon sight as shown and described.

DESCRIPTION

FIG. 1 is a perspective view of a weapon sight according to the present disclosure;

FIG. 2 is a front view thereof;

FIG. 3 is a right side view thereof;

FIG. 4 is a rear view thereof;

FIG. 5 is a top view thereof; and,

FIG. 6 is a left side view thereof, the bottom view forming no part of the claimed design.

The broken lines depict portions of the weapon sight that form no part of the claimed design.

1 Claim, 6 Drawing Sheets
